[57] CLAIM

The ornamental design for a combined multiple use and preparation unit, as shown and described.

DESCRIPTION

FIG. 1 is a front elevational view of a combined multiple use and preparation unit showing my new design;

FIG. 2 is a left side elevational view thereof;

FIG. 3 is a right side elevational view thereof;

FIG. 4 is a top plan view thereof;

FIG. 5 is a perspective view taken from the top, front and right side thereof;

FIG. 6 is a front elevational view of a second embodiment thereof, it being understood that the top and both sides are the same as top and both sides of the first embodiment; and,

FIG. 7 is a perspective view taken from the top, front and left side of FIG. 6.

FIG.1.

FIG.2.

FIG.3.

FIG.4.

FIG.5.

FIG.6

FIG.7
